APPLIANCE FOR SUPPLYING DRY STEAM TO COOKING OVENS

Filed Feb. 4, 1927

FIG.1.

FIG.2.

*Inventor
Charles de V. Grant
by Herbert W. Jenner,
Attorney.*

UNITED STATES PATENT OFFICE.

CHARLES DE VERE GRANT, OF HIGH HOLBORN, LONDON, ENGLAND.

APPLIANCE FOR SUPPLYING DRY STEAM TO COOKING OVENS.

Application filed February 4, 1927, Serial No. 165,862, and in Great Britain February 4, 1926.

For supplying dry steam in a gas or other cooking oven apparatus such as described in specification of prior Letters Patent granted to me No. 1,544,976 is especially designed.

Such apparatus comprises a steam generator arranged in the oven and provided with a longitudinally extending superheating chamber through the length of which the steam passes prior to issuing into the oven.

In practice it is found with such apparatus that the steam passes so quickly through the superheating chamber or through the pipe within the oven that it is not superheated to the extent desired and the object of the present invention is to provide in the said superheating chamber or the said pipe a device of any known or suitable type adapted to retard the flow of steam through said chamber or pipe.

Conveniently the retarding device 20 may be of the helical type that will cause the steam to take a helical path through the superheating chamber or pipe and deflect it towards the wall of the said chamber or pipe during such path. In this way the degree 25 of superheat is increased and the appliance is rendered more efficient.

The superheating chamber in the device described in the said specification No. 1,544,976 may and usually does consist of a tube 30 of circular cross-section to which saturated steam is admitted at or near one end and from which the dried or superheated steam passes into the oven through a hole or nozzle at or near the other end of the tube.

The accompanying drawing illustrates a device as described in the said prior specification No. 1,544,976 embodying the present invention.

Fig. 1 shows the device in sectional elevation, and

Fig. 2 is an end view partly in section corresponding to the line A A of Fig. 1.

1 indicates the steam generator to the sides of which are fixed supporting hooks 2 adapted to slide on bars fixed within an oven. 3 indicates the superheating chamber which consists of a tube of circular cross section fixed on the top of the generator 1. 4 indicates the filling funnel within which is fitted 45 a screw plug and safety valve, not shown. Saturated steam passes from the generator 1

into one end of the superheating chamber 3 through a pipe 5 and superheated steam leaves the said chamber and issues into the oven through a small hole 6 near the other 55 end of the superheating chamber. The retarding device according to the present invention consists of an appropriate length of helically twisted metal 7 adapted to fit within the superheating tube 3, the end of said 60 retarding device nearest the steam inlet 5 being shaped as shown so as to divide the flow of steam into two helical paths one on each side of the twisted metal body. The other end of the retarding device 7 terminates in a short axial stem 8 or is otherwise 65 so shaped as not to restrict the flow of superheated steam through the outlet or nozzle 6.

The length of the helical retarder 7 may, of course, be varied as found desirable and 70 in some cases the retarder may be formed in more than one section. Preferably it is formed in one piece as shown and extends the full length of the superheating tube 3.

The helical retarding device is shown as 75 being mounted stationary in the superheating chamber, and as being formed of an imperforate metal plate; it may however be mounted in any other approved way, and may be provided with any approved perforations.

What I claim is:

1. Means for supplying dry steam to an oven, comprising a steam generator, a steam superheating tube arranged horizontally and secured outside the steam generator to the top thereof, said tube having an inlet at one end communicating with the steam generator and having an outlet for dry steam at its other end, and a retarding device for the 80 steam arranged in the said tube.

2. Means for supplying dry steam to an oven as set forth in claim 1, the said tube being connected with the steam generator by a pipe which delivers the steam longitudinally of and at the axis of the tube, and the said retarding device being of a helical type and constraining the steam to flow in a helical path.

In testimony whereof I affix my signature.

CHARLES DE VERE GRANT.
